APPARATUS FOR PLAY AND SPORT

Rudolf Heimers, Mexico, D. F., Mexico

Application August 6, 1936, Serial No. 94,657
In Mexico August 7, 1935

9 Claims. (Cl. 272—40)

The invention relates to improvements in apparatus for play and sport in which a movable carrier for one or more persons is suspended by ropes or belts winding and unwinding themselves alternately on wheels connected with one or more flywheels, in order to produce alternate ascending and descending motions of the carrier with its load, incident to the momentum of the rotating flywheel, as has already been disclosed in the U. S. Patent No. 1,991,459.

The invention has for its object to provide devices of this class having mechanical or manual means for winding directly or indirectly the belts supporting the carrier on their respective wheels, until the carrier has reached its highest position or any desired height, whereupon the elements driving the shaft of the flywheel and the wheels carrying the winding means are disconnected, permitting said carrier to descend by its own weight and making it ascend again as the belts wind themselves in a contrary direction on the wheels continuing to rotate incident to the momentum of the rotating flywheel, such vertical reciprocating movements of the carrier being continued until brought to a stop by inertia of the flywheel, or by braking.

It is another object of the invention to provide means to permit a free and uniform play of the belts supporting the carrier at their point of connection to their wheels, so as to reduce to a minimum the wear on this place during their alternate winding and unwinding in both directions of rotation.

Different forms of construction of apparatus embodying the aforesaid features are shown in the accompanying drawings, in which:

Figure 1 shows an apparatus having a plurality of carriers with reciprocating motion mounted upon a central tower and rotatable in the form of a merry-go-round.

Figure 2 is a top view of the guiding member carrying the bar acting as a carrier.

Figure 3 is a lateral view of the same guiding member.

Figure 4 shows another apparatus in which the initial ascending motion of the carrier is obtained by alternate pulling of two ropes by the person sitting on the carrier.

Figure 5 is a sectional view on line a—a of Figure 4, showing the arrangement of the gears operating the flywheels.

Figure 6 is a top view of the apparatus shown in Figure 4.

Figure 7 is a sectional view on line b—b of

Figure 4, of one of the supports of the apparatus, with the shock-absorbing device.

Figure 8 represents still another embodiment of the apparatus, in which the initial ascending motion is obtained by pedals.

Figures 9 and 10 illustrate two different positions of the connecting and disconnecting mechanism of the apparatus shown in Figure 8.

Figure 11 is a top view of the supporting levers and of the disconnecting lever of the mechanism shown in Figures 9 and 10.

Figure 12 shows a device for lengthening and shortening the belts supporting the carriers.

The apparatus shown in Figure 1 is constructed in form of a merry-go-round, with a stationary central supporting tower 1 and a vertical shaft 2 rotatable through conical gears 3 from a motor not shown. On top of the tower 1 there is mounted a conical gear wheel 4 fixedly supported by a cylindrical hollow member 2a and engaging a number of smaller conical gears 5 mounted on the inner ends of radially extending shafts 6 which pass through bearings suspended from horizontal arms 7 extending radially in the known manner from a central hub 8 secured above the conical gear wheel 4 to the shaft 2, the outer extremities of the arms 7, united by braces 9, being suspended from the top of the shaft 2 by bars 10, following the usual construction of merry-go-rounds.

Each one of the horizontal shafts 6 carries suspended from two of its bearings 6a, a frame 11 bent in form of a U and preferably made from metal tubes, the lower parts of these frames almost reaching the ground or the platform on which the apparatus is mounted. Attached to the inner lower part of said frame there are rollers 12 bearing against a metal ring 13 placed around the lower part of the tower 1, said rollers acting as guides preventing the contact of the frames 11 with the legs of the tower 1.

Between the bearings 6a are placed on the shafts 6 the wheels 14 having lateral flanges which leave a central portion for the winding and unwinding of the belts 15. Each of said shafts 6 also carries a flywheel 16.

The lower extremities of the belts 15 of each shaft 6 are secured to a horizontal bar 17, the ends of which are provided with guiding members (Figures 2 and 3) comprising a U-shaped casing 18 for straddling the vertical side tubes of frame 11, and a pivoted arm 19 supporting a roller 20 normally held spaced from the tube 11 by stops 22 against which the arm 19 is attracted by springs 21, so as to bring said roller 20 in con-

tact with the tube 11 only in case the bar 17 takes an oblique position through rupture of one of the belts 15, in which case said roller acts as a brake. Friction-reducing means such as rotating metal balls 24 are provided within the casing 18 and bear against the outside of the tubes 11. Elastic shock absorbers 26 at the lower part of the frames 11 receive the guides of the carriers 17 in case of rupture of the belts 15.

10 On the bars 17 may be mounted a wooden horse 23 or any other figure, support or seat, or a plurality of them, on which sit or stand the persons using the apparatus.

As the merry-go-round is rotated by its central shaft 2, the stationary conical gear 4, not connected to said shaft rotates the gear wheels 5, the shafts 6, the wheels 14 and the flywheels 16. The belts 15 are thereby wound on the wheels 14 and the carriers 17 ascend together with the persons supported by them. As said carriers reach their uppermost desired position, vertical stops 27 extending from the inner guiding members 18 are thrust against the extremity of angular levers 28 pivoted to the frame 11, and these levers 25 through a set of articulated levers 29 and 30, displace the conical wheels 5 slidably mounted on the shafts 6 so as to disengage them from the central wheel 4. The shafts 6 may therefore turn freely and the carriers 17 with the persons supported by them descend rapidly until the belts 15 are completely unwound. The momentum attained by the flywheels 16 during the descent of the carriers 17 causes them to continue their rotation and the belts of each shaft are again 35 wound up on the wheels 14, in a contrary direction, producing thereby a second automatic ascent of the carriers 17. The vertical reciprocating movement of the carriers continues for a certain time, on a proportionally reduced scale, 40 until it stops through inertia of the flywheels 16. The rotation of the central shaft 2 is stopped by the brake band 31, and the conical wheels 5 are again brought into engagement with the central stationary wheel 4 by pulling on a line 32. 45 Another line 25 attached to the levers 28 permits the disconnection of the gears 4 and 5 to be effected at any time.

In the apparatus described, the initial ascent of the persons using it is obtained by mechanical means independently of human action. In the following embodiments of the invention, the initial ascent is produced by direct intervention of the persons making use of the apparatus, whereby different parts of the body are brought into 55 play and exercised.

The apparatus represented in Figure 4 comprises two vertical supports consisting preferably of U-irons 33 on the outside and T-irons 34 on the inside, both secured together and the latter 60 serving as guides. The upper extremities of said supports are connected by a rectangular frame consisting of two horizontal beams 35 separated at the ends by transverse beams 36 attached to the uprights.

65 Slidably disposed along the inner T-irons 34 there is a frame comprising an upper horizontal bar 37 and a lower horizontal bar 38, both united by vertical bars 39. Instead of bars, pipes may also be used. The extremities of the horizontal members 37 and 38 are provided with guiding members 40 comprising a slotted piece with an inner layer 41 of fibre or other suitable material, engaging the inner edge of the T-irons 34. On the lower bar 38 is mounted a seat 42 with supports 43 for the feet, and a railing 44 secured to

the vertical members 39 prevents the person sitting on the seat 42 from falling off.

On the transverse members 36 of the upper frame are mounted two bearings 45 through which passes a shaft 46 carrying at each end a flywheel 47 and inside of the frame two flanged wheels 48 to which are fastened the belts 49 which are also connected to the top of the frame 37-38 forming the carrier. For enabling the persons sitting on said carrier to wind the belts 49 on the wheels 48 and thereby to start by their efforts the initial ascending movement of the carrier, the following device is used.

On the shaft 46 are mounted towards its center two spaced conical gears 50 facing each other. Each of these gears engages another conical gear 51, the shafts of which, outside of their bearings, are bent at right angles and support flanged wheels 52, disposed in such a manner that each wheel is situated on a line eccentrically prolonging that of the other wheel, in opposite directions, as shown in Figures 4, 5, and 6. To the inner portion of these wheels 52 are attached belts or ropes 53, each one of which passes between a pair of rollers 54 mounted on supports 55 attached to the under side of the beams 35 and bringing said belts or ropes into close proximity. Each belt or rope 53 is provided at its lower end with a handle 56 and also passes through guides 57 secured to opposite sides of the bar 37.

The person occupying the seat 42 grasps the handles 56 and starts pulling down alternately each belt or rope 53. Due to the opposite position of the wheels 52 which prevents the conical gears 51 from ever being at a dead point, these gears start to rotate in the same direction the gears 50 together with the shaft 46 and the flywheels 47. These flywheels, through the momentum acquired, produce the winding of the belts 49 on the wheels 48 and the carrier is raised. As the shaft 46 continues its rotation, the gears 51 are completely rotated and with them the wheels 52 which turn around the shafts of said gears, whereby the belts or ropes 53 are wound around said wheels 52 proportionally to their shortening 45 due to the ascent of the carrier. Suitable stops 58 provided on the belts or ropes 53 limit the extent of the pulling motions.

When the carrier 37-38-39 has reached its uppermost position, its upper guiding members 50 strike against levers 59 pivoted to the supports 33 and operate by means of a rope 59a the brakes 60 provided on one side of the flywheels 47. These brakes can also be operated manually by means of levers 61 connected to the same 55 ropes 59a, at a low position of the carrier when it is desired to prevent said carrier from ascending again.

From its highest position the movable carrier, after a temporary application of the brakes 60 on the flywheels 47 as described, descends again by its proper weight and the reciprocating vertical movements of the carrier continue until stopped by inertia.

In case of a rupture of one or both belts 49 a shock absorber has been provided on both sides of the apparatus, comprising springs 62 mounted within the U-irons 33 and supporting each a plate 62a, against which strike two bent arms 63 fastened to the sides of the upper guides 40.

The vertical members 39 of the carrier may be disconnected from the upper bar 37 by loosening the couplings 64 and the lower part of the carrier may be removed. To the remaining upper bar may be attached some gymnastical appara-

tus, such as the rings 65 shown in Figure 4, in order to execute gymnastic exercises during the reciprocating movements of the carrier.

In the apparatus illustrated in Figure 8, use is made of pedals for effecting the initial ascent of the carrier. In this apparatus, two vertical supports 66 duly braced carry at their upper ends a horizontal shaft 67 provided on one end with a flywheel 68 with its corresponding brake 69 and towards the center with two conical gears 70 and two flanged wheels 71 connected to the belts 72. The gears 70 engage other conical gears 73 secured to the upper ends of vertical bars 74 provided with longitudinal slots 75 and slidably supported in upper brackets 76 fastened to the supports 66 and lower brackets 77 mounted on the base of the apparatus. The lower extremities of the bars 74 rest on the ends of centrally pivoted levers 78 and 78^a, one of which (78^a) is provided with a sidewardly extending pin 79, whilst the other lever 78, with its extremity bent downward in form of a Z, catches from below the opposite lever 78^a carrying the pin 79, as shown in Figures 9 and 10. The pin 79 is detained by a catch 80 pushed forward by a spring 81, whereby the levers 78 and 78^a are maintained in the position shown in Figure 8 with their outer ends raised and supporting the bars 74 in a position in which their upper gears 73 engage the gears 70 of the shaft 67. Slidably mounted on the bars 74 are the tubes 82 united by transverse tubes 83 providing a carrier frame suspended from the lower ends of the belts 72. On the lower tube 83 are mounted the seats 84 and below this tube, sustained in the center by a support 85, are mounted the pedals 86, the ends of which carry the worm wheels 87 engaging other worm wheels 88 mounted loosely on the bars 74, below the tubes 82. The worm wheels 88 engage with an inwardly extending pin 75 of the bars 74, so as to transmit their rotation to them, enabling at the same time said worm wheels to ascend and descend along the bars 74. The two sets of worm wheels 87 and 88 are housed in casings 89 fixed to the tubes 82 and shown in dotted lines in Figure 8.

As the persons occupying the seats 84 move the pedals 86, the worm wheels 88 are rotated and communicate their rotation to the bars 74 as described. The gears 73 connected to said bars 50 rotate the gears 70 and consequently the shaft 67, the flywheel 68 and the wheels 71, whereby the belts 72 are wound on said wheels 71 and raise the carrier 82-83 with the persons sitting on it. As this carrier reaches its highest desired position, an arm 90 extending from the upper part of said carrier strikes a stop 91 on a rope 92 attached with its upper end to a spring 93 suspended from the bracket 76, and with its lower end to the outer extremity of the lever 94, the opposite extremity of which, pushed upwardly by a spring 95 stronger than the spring 93, engages from above the pin 79 of the lever 78^a. As the rope 92 is pulled upward by the arm 90 striking the stop 91, it pulls down the opposite end 65 of the lever 94 and this end first slides down along the inclined surface of the upper part of the catch 80 (Figure 11), disengaging the pin 79, and immediately afterwards bears against an inclined projecting surface 80^a provided transversally on said catch and pushes the latter backward, freeing the pin 79 from engagement with said catch. The weight of the bars 74 on the ends of the levers 78 and 78^a depresses these levers (Figure 9) and as the bars 74 descend, 70 their gears 73 are disengaged from the gears 70. 75

The carrier 82-83 then slides down along the bars 74 without the pedals being moved and continues its vertical reciprocating movements until stopped by inertia. Shock absorbers in form of springs 96 supported on the lower brackets 77 and surrounding the bars 74 receive the impact of the carrier in case of rupture of one or both belts 72.

For returning the levers 78 and 78^a to their former positions, with the bars 74 raised and the gears 70 and 73 engaged, the rope 92 is pulled upward, whereby the inner extremity of the lever 94, being in the position shown in Figure 10 after having returned from the position of Figure 9, engages the pin 79 and pushes it down, together with the levers 78 and 78^a, until said pin is caught again under the catch 80.

For applying the brake 69 to the flywheel 68 during the reciprocating motions of the carrier 82-83, another rope 97 has been provided, connected with said brake 69 and passing between a set of three rollers 98 extending from a casing 99 attached to one of the tubes 82, the braking effect being obtained by shortening said rope 97 through displacement of the middle roller by 25 suitable means 100 against the fixed rollers.

In Figure 12 has been shown a device by means of which the belts supporting the carriers in all of the embodiments shown may be lengthened or shortened. It is advisable, for instance, to dispose of a reserve length of belt in case it should break at its point of attachment to its corresponding wheel, where it is most likely to wear out. The device consists of a short length of tube 101 loosely mounted on the bar to which the lower extremity of the belt is attached, and provided with means such as collars, screws etc. to secure it rigidly to said bar. Around this outer tube 101 is placed and clamped a collar 102 formed of two parts and having an opening at 40 its center within which a certain length of the belt is wound around the tube 101, this belt passing afterwards alternately through a series of slots provided in an extension formed on one part of the collar 102 and being pressed against 45 one of the solid parts of said extension by a transversal metal strip 104 attached by screws 105.

A preferred mode of fastening to their respective wheels all of the belts supporting the carriers is shown applied to the wheels 52 of Figure 50 4, in which is shown the end of the belt riveted to a bent metal strip through which passes a bolt 107 crossing the wheel. Back of this bolt there is a recess in the cylindrical middle portion 106 of the wheel, on which the belt is wound, so that as the direction of rotation of the wheel is reversed, the end of the belt may freely turn on its bolt without being bent at this place.

Obviously, changes in the details of construction may be made without departing from the spirit of the invention, and therefore I do not wish to limit myself to the specific constructions shown and described.

What I claim is:

1. Apparatus for play and sport, comprising a flywheel mounted upon a shaft at an elevated point for rotation in reverse directions, a carrier element below the flywheel, wheels upon the said shaft rotating with the flywheel, driving means for the said shaft, winding means connected to said wheels to be wound and unwound thereon, and also connected to the carrier element, and means connecting and disconnecting the driving elements of the shaft carrying the flywheel and the wheels for the winding means, 65 70 75

the carrier element being arranged for vertical reciprocating movement to impart reverse rotations to the flywheel and for being pulled thereafter by the winding up of the winding means incident to momentum of the rotating flywheel.

5. Apparatus as claimed in claim 1, including a plurality of said vertically movable carrier elements arranged radially around a central support, and means for rotating said central support 10 and the carrier elements.

6. Apparatus as claimed in claim 1, including a plurality of said vertically movable carrier elements, a central rotatable support having said carrier elements radially disposed around it, 15 means operated by the rotation of said support to impart initial rotation to the flywheels and the wheels connected to the winding means, and means operated independently from the rotation of said support to engage and disengage the driving elements imparting the rotation to the fly- 20 wheels.

7. Apparatus as claimed in claim 1, in which the means imparting initial rotation to the flywheel and the wheels connected to the winding 25 means comprise elements for rotating the shaft of said flywheel and said wheels by alternate pulls on ropes effected by the person occupying the carrier element.

8. Apparatus as claimed in claim 1, including 30 braking means for the flywheel operated automatically by the ascending carrier element and independently by the person occupying the carrier element.

9. Apparatus as claimed in claim 1, in which 35 the means imparting rotation to the flywheel and

the wheels connected to the winding means comprise pedals operated by the person occupying the carrier element and actuating the elements rotating said flywheel and wheels, and means operated by the person occupying the carrier element for applying a braking action to the flywheel.

10. Apparatus as claimed in claim 1, in which the means imparting rotation to the flywheel and the wheels connected to the winding means 10 comprise pedals operated by the person occupying the carrier element and actuating the elements rotating said flywheel and wheels, means operated by the person occupying the carrier element for applying a braking action to the 15 flywheel, vertically movable supports on which the carrier element is slidably mounted, and pivoted elements on which said movable supports rest and which during the ascent of the carrier element cause engagement of the elements rotat- 20 ing the flywheel and when the ascent is completed cause said movable supports to drop out of engagement with said elements rotating the flywheel.

11. Apparatus as claimed in claim 1, in which 25 belts forming the winding means or attached to their respective wheels by a doubled end surrounding a bolt transversally mounted in said wheels, the central portion of said wheels having a recess permitting free movement of said 30 doubled end.

12. Apparatus as claimed in claim 1, including 35 adjustable means for taking up a surplus of the winding means secured to the carrier element.

RUDOLF HEIMERS. 35
